J. WORLEY, JR

DOOR LATCH

Filed Sept. 21, 1925

Inventor
John Worley, Jr.

Attorney.

UNITED STATES PATENT OFFICE.

JOHN WORLEY, JR., OF LOS ANGELES, CALIFORNIA, ASSIGNOR TO WORLEY & CO., OF LOS ANGELES, CALIFORNIA, A CORPORATION OF CALIFORNIA.

DOOR LATCH.

Application filed September 21, 1925. Serial No. 57,569.

This invention relates generally to latches for lockers, cabinets and the like, and is more particularly concerned with, though not limited to, latching mechanism for doors 5 of relatively small lockers or boxes wherein a single oscillatory latching element, pivoted on the inner side of the door, is adapted to engage a keeper on the door frame and thereby releasably hold the door closed. 10 In a co-pending application for patent or door latch, No. 714,324, filed May 19, 1924, by Elmer L. Vreeland and myself as joint inventors, is shown a latch of this general description, there being a handle extension 15 on the latch which extends through a suitable opening to the outer face of the door. The handle is of such weight that it normally retains the latch in latching position, and is utilized to rock the latch about its 20 pivot to release it from engagement with the keeper.

In the present invention, the latch handle is formed and bent in such a manner that, though there is no increase in the size of 25 weight thereof, it is better able to withstand ordinary wear or tear or even abusive treatment, within reasonable limits. Furthermore, it is of a nature to defeat all ordinary attempts to spring the latch from engagement with the keeper by pressure directed laterally against the handle at the outside 30 of the door. The advantages of such features are self-evident.

Further objects and features of novelty 35 will be apparent from the following description, reference being had to the accompanying drawings, in which:

Fig. 1 is a front elevation of a box locker equipped with an embodiment of my invention;

Fig. 2 is an enlarged section on line 2-2 of Fig. 1, the latch, however, being shown entirely in elevation;

Fig. 3 is a view similar to Fig. 2 but showing the latch moved out of engagement with its keeper;

Fig. 4 is a view showing the inner face of the locker door with its associated latch mechanism, one of the side walls of the 50 locker being shown in section; and

Fig. 5 is a horizontal section on line 5-5 of Fig. 4.

In the drawings, I have illustrated the latch associated with a locker box made up of an angle iron door frame and sheet metal 55 sides, while the door is shown as consisting of a sheet metal plate having inwardly turned, marginal flanges. However, it will be understood this specific showing is made merely for purpose of aiding in the clear 60 description of a typical latch installation, and is not to be construed as limiting the application of the invention to this particular type of locker. Furthermore, while I have shown the latch hook as being adapted 65 to engage the keeper from beneath, it lies within the scope of the broader claims to arrange the latch so that it is adapted to engage the keeper from other sides, or so it may operatively engage keepers other than 70 those of the particular form illustrated.

The door frame 10, to which the side door and bottom plates P of the locker are secured, consists of horizontal angle irons 11 and vertical angle irons 12 and 13. Door 75 14 is made up of plate 15 having inwardly turned marginal flange 16 and is hinged to frame iron 13 at 17. The flange at the opening side of the door is designated as 16^a. Keeper 18 is secured to frame iron 12 at 19 80 and has a portion 20 which approximately parallels flange 16^a when the door is closed (see Fig. 5), a bar 21 extending across the inner edge of said flange.

Oscillatory latch 23 includes a body portion 24 which is pivotally connected at 25 to the inner side of flange 16^a, and is adapted to oscillate vertically in a plane adjacent and substantially parallel to the plane of said flange. The latch has a hook 26 with an 85 upwardly opening mouth 27, handle 28 and lock element 29. Nose 30 of hook 26 has a cam face 31, while notch 32 in the lower edge of the handle provides opposed stop shoulders 33, 34. The handle inclines outwardly and downwardly to provide a shoulder 36, for a purpose to be described later. The latch extends through a slot 35 provided in door plate 15 adjacent flange 16^a, and the weight and disposition of handle 100 28 are such that the handle tends to swing the latch in a clockwise direction as viewed in Fig. 2, shoulder 34 being adapted to engage the outer face of door plate 15 to limit

the extent of this latch movement, and thus serving to establish the latching position of the latch.

With the door closed and the latch in latching position (see Fig. 2) the major portion of element 29 extends horizontally beyond the outer face of door plate 15, and hook 26 is in position to engage cross bar 21, as clearly shown in Fig. 2, this engagement being adapted to hold the door closed until the latch is rotated in a counter-clockwise direction by manually lifting handle 28 into the position shown in Fig. 3.

The device as so far described is generally similar to that of the aforementioned co-pending application, with the exception that bar 21 is not here extended to lie along the side of nose 30, as is true in the latch shown in said application.

In the present device, however, portion 37 of handle 28 is bent to lie in a plane substantially perpendicular to body portion 24 and inclines inwardly and downwardly from shoulder 36 so shoulder 38 at the bottom of portion 37 extends transversely from body portion 24 and preferably, though not necessarily, substantially parallel to the pivotal axis of the latch. Shoulder 38 is adapted to lie close to or engage the outer face of door 14, and is preferably of sufficient length to extend horizontally over the parting line between door and frame, and well onto frame iron 12, when the door is closed.

Preferably, the terminal of the handle is bent outwardly as shown in Figs. 2 and 5, to provide a lip 39 which lies clear of the outer face of the frame so the handle may be easily raised by the operator. The described bending of the handle, which brings shoulder 38 into a position horizontally off-set from the plane of nose 30 and from the point of pivotal connection between body member 24 and flange 16^a, not only stiffens member 23, but also prevents the latch from being sprung from keeper bar 21 by prying or bending horizontally in one direction on the handle portion. If the handle be forced to the left in Fig. 5, member 23 merely pivots horizontally at 25 (assuming, of course, that the handle has some lateral play at its pivot point) throwing hook 26 to the right on the keeper until flange 16^a prevents further horizontal pivotal movement.

On the other hand, the engagement of shoulder 38 with the outer face of the door and door frame prevents the handle from being sprung to the right in Fig. 5, and hence prevents hook 26 from being moved laterally off the free end of keeper bar 21. This eliminates the necessity of a terminal stop on said free end.

Of course, it is not necessary that shoulder 38 normally engage frame iron 12 when the

door is closed, though it should lie close thereto, for bar 21 is of such length that the hook remains fully engaged therewith if the latch has only slight horizontal pivotal movement.

The advantage of thus guarding against malicious forcing of the door is obvious.

When handle 28 is lifted, shoulder 33 is adapted to engage the inner face of door plate 15 to limit the counter-clockwise movement of the latch after hook 26 clears bar 21, and with the parts thus put into position of Fig. 3, it is obvious that the door may then be swung open by a continued outward pull on handle 28. When the operator releases handle 28 the latch gravitates back to latching position. Upon subsequently closing the door, no manipulation of the latch is necessary, for, during closing movement, the cam edge of nose 30 engages the forward lower edge of bar 21 causing the latch to rotate in a counter-clockwise direction until the door is closed, whereupon nose 30 clears the keeper bar and allows the latch to gravitate back to position of Fig. 2.

I have illustrated two locking devices for the door, both devices acting directly upon the latch to prevent its movement out of latching position except by the holder of proper keys or by knowledge of a particular lock combination. Either or both of these lock devices may be used in connection with a given locker.

I have shown a lock 40, either of combination or key operated type, fastened to the side of the door at 41, and having a usual lock nose 42 extending to the outer face of door 14. Lock 40 has a bolt 43 which, when fully extended, engages or lies in the path of vertically extending shoulder 44 of lock element 29 when the door is closed and the lock is in operating condition, bolt 43 thus being adapted to co-act with element 29 to prevent the latch from being rotated out of latching position.

Element 29 is also provided with an aperture or eye 45 which is adapted to receive the shackle or bolt 46 of padlock 47, it being obvious that the shackle is adapted to engage the outer face of the door to prevent rotation of the latch out of latching position. The body of the padlock is adapted to rest on inclined portion 36, and is thus held from contact with the face of the door where it may be easily grasped and manipulated, and so it may not swing to and fro in a manner to mar or scratch the door finish.

It will be noted that the latch may be made up of a single metal stamping, and that its attachment involves only the provision of a narrow slot in the door and a single pivotal mounting. While I have specified that the latch is pivoted on flange 16^a and is adapted to oscillate in a plane parallel to that flange,

it will be understood it lies within the scope of the invention to pivot the latch elsewhere on the door, though the illustrated arrangement is preferred.

- 5 It will be understood the drawings and description are to be considered merely as illustrative of and not restrictive on the broader claims appended hereto, for various changes in design, structure and arrangement may 10 be made without departing from the spirit and scope of said claims.

I claim:

1. In combination, a locker having a door hinged thereto, a keeper on the door frame, an oscillatory latch pivoted on the inside of the door for vertical oscillatory movement, a handle on the latch extending through the door whereby the latch is adapted to be oscillated from the outside of the door into and out of latching engagement with the keeper, and a shoulder on the handle and horizontally offset from the point of pivotal connection between the door and latch, said

shoulder being adapted to lie adjacent the outer face of the door when the latch is engaged with the keeper.

2. In combination, a locker having a door hinged thereto, a keeper on the door frame, an oscillatory latch pivoted on the inside of the door for vertical oscillatory movement, a handle on the latch extending through the door whereby the latch is adapted to be oscillated from the outside of the door into and out of latching engagement with the keeper, a portion of said handle at the outside of the door being bent angularly to bring it into offset horizontal relation with the point of pivotal connection between the door and latch, and a shoulder on said portion adapted to lie adjacent the outer face of the door when the latch is engaged with the keeper.

In witness that I claim the foregoing I have hereunto subscribed my name this 22nd day of August 1925.

JOHN WORLEY, JR.
